US00D793616S

(12) **United States Design Patent** (10) **Patent No.:** **US D793,616 S**
(45) **Date of Patent:** ** *Aug. 1, 2017

(54) **LIGHT FIXTURE**

- (71) Applicant: **IP Holdings, LLC**, Vancouver, WA (US)
- (72) Inventor: **Christopher Reynolds**, Vancouver, WA (US)
- (73) Assignee: **IP Holdings, LLC**, Vancouver, WA (US)
- (*) Notice: This patent is subject to a terminal disclaimer.
- (**) Term: **14 Years**
- (21) Appl. No.: **29/516,347**
- (22) Filed: **Jan. 30, 2015**

Related U.S. Application Data

- (63) Continuation of application No. 29/502,094, filed on Sep. 11, 2014, now Pat. No. Des. 732,236.

(57) **CLAIM**

The ornamental design for a light fixture, as shown and described.

DESCRIPTION

FIG. 1 is a perspective view of a light fixture, as viewed from below, showing my new design;
FIG. 2 is a perspective view of the light fixture shown in FIG. 1, as viewed from above;
FIG. 3 is a left side view of the light fixture shown in FIG. 1;
FIG. 4 is a right side view of the light fixture shown in FIG. 1;
FIG. 5 is a front elevation view of the light fixture shown in FIG. 1;
FIG. 6 is a rear elevation view of the light fixture shown in FIG. 1;
FIG. 7 is a top plan view of the light fixture shown in FIG. 1; and,
FIG. 8 is a bottom plan view of the light fixture shown in FIG. 1.
The broken lines shown in the drawings illustrate portions of the light fixture that form no part of the claimed design.

1 Claim, 6 Drawing Sheets
